UNITED STATES PATENT OFFICE

161,225

RUBBER MAT OR SIMILAR ARTICLE

Ada Westrate, Chicago, Ill., assignor, by mesne assignments, to The Buxbaum Company, Canton, Ohio, a corporation of Ohio

Application November 23, 1949, Serial No. 6,224

Term of patent 7 years

(Cl. D9—6)

To all whom it may concern:

Be it known that I, Ada Westrate, a citizen of the United States, residing at Chicago, in the county of Cook, and State of Illinois, have invented a new, original, and ornamental Design for a Rubber Mat or Similar Article, of which the following is a specification, reference being had to the accompanying drawing, forming part thereof, in which:

The figure is a top plan view of a rubber mat, showing my new design. The mat is flat and of conventional thickness.

The dominant features of my design reside in those portions shown in full lines.

I claim:

The ornamental design for a rubber mat or similar article, substantially as shown and described.

ADA WESTRATE.
